UNITED STATES PATENT OFFICE

157,274

SPOON OR SIMILAR ARTICLE OF FLATWARE

Allison R. Macomber, Taunton, Mass., assignor to National Silver Company, New York, N. Y., a corporation of New York

Application November 25, 1949, Serial No. 6,247

Term of patent 14 years

(Cl. D54—12)

To all whom it may concern:

Be it known that I Allison R. Macomber, a citizen of the United States, residing in the city of Taunton, county of Bristol, State of Massachusetts, have invented a new, original, and ornamental Design for a Spoon or Similar Article of Flatware, of which the following is a specification, reference being had to the accompanying drawing, forming a part thereof, in which:

Fig. 1 is a front elevation of a spoon or similar article of flatware showing the essential features of my new design in full lines.

Fig. 2 is a rear elevation thereof.

Fig. 3 is a section taken on line 3—3 of Fig. 1.

I claim:

The ornamental design for a spoon or similar article of flatware, as shown and described.

ALLISON R. MACOMBER.
